UNITED STATES PATENT OFFICE.

GEORGE F. HUTCHINS, OF WORCESTER, MASSACHUSETTS.

LOOM.

SPECIFICATION forming part of Letters Patent No. 645,525, dated March 13, 1900.

Application filed June 25, 1898. Serial No. 684,470. (No model.)

To all whom it may concern:

Be it known that I, GEORGE F. HUTCHINS, a citizen of the United States, residing at Worcester, in the county of Worcester and 5 State of Massachusetts, have invented certain new and useful Improvements in Looms, of which the following is a specification.

My invention relates to a certain class of looms for making velvet, plush, &c., in which 10 the fabric is woven double and two shuttles for putting in the filling are employed which are thrown across the loom simultaneously, one traveling on the lay and the other traveling on some of the warp-threads. The double fabric, or two fabrics, are cut apart by a 15 knife attachment connected with the loom to form two fabrics with the pile on each.

My invention relates particularly to mechanism for regulating the tension on the pile- 20 warps, or the warps which form the pile of the fabrics, as the loom is operated.

It will be understood that in the class of 25 looms above referred to there are two sets of ground-warps, ordinarily cotton warps, to form the bodies of the two fabrics woven on the loom. Each set of said warps is drawn into two sets of harnesses which are so arranged and operated as to weave two separate and independent fabrics at the same time, 30 and the harnesses for the set of warps forming one fabric, as the top fabric, travel up and down to form a shed for the top shuttle, while the harnesses for the set of warps forming the other fabric, as the lower fabric, travel 35 up and down to form a shed for the lower shuttle, which shuttle travels on the lay.

In connection with the warp-threads forming the body of the fabric additional warp-threads are employed to form the pile. The 40 pile-warp threads must be connected with the body-warp threads of each of the two fabrics woven on the loom, and they act to join the two fabrics together upon their inner or contiguous faces to form one fabric until cut 45 apart by a knife attachment, which leaves two independent fabrics, with the cut pile on the inner face of each.

The pile-warps are ordinarily carried from the pile-warp beam over a guide-rod to a 50 spring-tension-regulating rod and from said rod to the harnesses which control the move-

ment of the pile-warps in the ordinary way in the class of looms above referred to.

It will be understood that the pile-warp harnesses operate to carry a part of the pile-warps into the upper part of the top shed and a part of them into the bottom part of the bottom shed, and vice versa, for the two shuttles and also carry the pile-warp threads to an intermediate point.

By reason of the divergence and the different angles at which the pile-warps extend when they are in the two different positions above mentioned there is a slackening of the pile-warps at their intermediate position— 65 that is, the distance from this position to the tension-regulating rod is not so great as from the other position of the pile-warp threads to the tension-regulating rod. To overcome this and have the pile-warps of the same length in 70 the fabric in whatever position the pile-warp harnesses may be, it is necessary that the tension-regulating rod for the pile-warp threads should be moved toward and away from the cloth-point of the fabric to regulate the ten- 75 sion on the pile-warps.

Heretofore a spring has been used in this class of looms above referred to to actuate the tension-rod, so that the movement of the tension-rod for the pile-warps was spring-actuated and therefore was not always moved to the same position, and consequently the length of the pile-warps in the fabric was likely to vary, according to whether the harnesses of the pile-warps were in one position 85 at the top and bottom of the double fabric or in the intermediate position.

The object of my invention is to provide in 90 looms of the class above referred to mechanism for positively moving the tension-regulating rod for the pile-warps, so that said rod will be moved a predetermined distance to regulate the tension on the pile-warps.

My invention consists in certain novel features of construction of my positive tension- 95 regulating device for the pile-warps in looms of the class referred to for weaving velvet, plush, &c., as will be hereinafter fully described.

The drawing shows a portion of a loom 100 frame or arch and the rods over which the ordinary warp-threads pass and also the rods

over which the pile-warps pass, with my mechanism for positively moving the pile-warp tension-regulating rod combined therewith.

In the drawing, 1 is a portion of the loom frame or arch at one side of the loom.

2 and 3 are the rods over which the two sets of warp-threads 4, forming the body of the two fabrics, pass in the ordinary way.

5 is the rod, over which the pile-warp threads 6 pass from the pile-warp beam. (Not shown.) Said pile-warps pass under the tension-regulating rod 7, which is supported at each end in a slot in the upper end of the arm 8, having a hub 8', which is fast on a rock-shaft 9.

Extending out from the hub 8' toward the front of the loom is an arm 10, which is connected at its end by a spring 11 with a stationary arm 12, secured to the loom-frame.

20 Extending in an opposite direction to the arm 10 from the hub 8' is an arm 13, having a longitudinal slot 13' therethrough. The slotted arm 13 is connected through a rod or connector 14 with an arm 15, having a longitudinal slot 15' therethrough.

25 The arm 15 is pivoted on the lower end of a bracket or arm 16, secured at its upper end on the loom-frame.

30 By means of the slots 13' and 15' in the arms 13 and 15, respectively, the point of connection of the rod 14 with each of said arms may be varied, if desired to increase or decrease the movement of the tension-rod 7.

35 On the free end of the arm 15 is mounted a roll 17, which is adapted to engage the periphery of a cam 18, in this instance of eccentric shape and bolted to the inner face of a gear 19, loose on a stud 20. The gear 19 meshes with a pinion 21, fast on a shaft 22, which carries at its opposite end a beveled gear 23, which meshes with a beveled gear 24, fast on the upright driven shaft 25.

40 The revolution of the shaft 25 through beveled gears 24 and 23, pinion 21, and gear 19, will communicate motion to the cam 18, and through roll 17, arm 15, connector 14, arm 13, and arm 8 the tension-rod 7 will be moved inwardly and outwardly, the spring 11 acting to keep the roll 17 in contact with the cam 18.

45 50 It will be seen that when the pile-warps 6 are at the middle position intermediate the bottom and top shed, as shown in the drawing, the tension-rod 7 will be at its rearward position, brought there and held there by the

55 cam 18 acting on the roll 17, and when the pile-warp threads 6 are in the top and bot-

tom sheds the tension-rod 7 will be at its forward position, the shape and revolution of the cam 18 being so regulated as to bring the roll 17 on the lowest part of the cam at this 60 time.

On the cam 18 (shown in the drawing) there is one high portion and one low portion, said cam being of eccentric shape, and therefore a single revolution of said cam will cause the 65 tension-regulating rod 7 to be moved once into its forward position and once into its rear position. The revolution of the cam 18 is so timed as to cause one revolution of said cam for every two picks of the loom.

70 The operation of my mechanism for positively moving the tension-regulating rod at the proper time will be readily understood by those skilled in the art.

75 The details of construction of some of the parts of my mechanism may be varied, if desired, and instead of mounting the operating mechanism above the tension-regulating rod, as shown, it may, if desired, be mounted below it or in some other position.

80 Having thus described my invention, what I claim as new, and desire to secure by Letters Patent, is—

1. In a loom for weaving velvet, plush, &c., the combination of a rock-shaft, arms connected thereto, a tension-regulating rod for the pile-warp carried by said arms, a second arm carried by the rock-shaft, a spring connected to said second arm and tending to normally turn the rock-shaft in one direction, 85 and means for moving the rock-shaft against the tension of said spring, comprising a cam, a pivoted arm carrying a roll traveling on said cam and a rod connecting the pivoted arm and rock-shaft.

90 2. In a loom for weaving velvet, plush, &c., the combination of a rock-shaft, arms connected thereto and carrying a tension-regulating rod for the pile-warps, a second arm carried by the rock-shaft, a spring acting on 100 said arm to normally turn the rock-shaft in one direction, and means for turning the rock-shaft against the tension of said spring comprising a cam, a pivoted slotted arm carrying a roll traveling on said cam, a slotted arm secured to the said rock-shaft and a rod connecting said arms and adjustable in the slots 105 thereof.
